UNITED STATES PATENT OFFICE

JAMES G. TOMPKINS, OF VENICE, CALIFORNIA

CLASP FOR BANDAGES AND LIKE WRAPPINGS

Application filed April 28, 1931. Serial No. 533,443.

This invention relates to an improved clasp which is particularly well adapted for affixing catamenial bandages to belts or other supports as well as for supporting and reliably maintaining in place other bandages and wrappings.

An object of the invention is to provide a simple, small inexpensive easily operable and most reliable clasp which will do away with the necessity of employing bothersome and cumbersome hooks, safety pins and other fastenings as now generally employed for the purposes aforementioned and therefore eliminate the difficulties attending the affixation of bandages et cetera with said hooks, pins, etc.

Another object is to provide a clasp of the character described which primarily comprises a simple form of clasp element similar to the clasp forming the subject matter of my former application, Serial Number 466,951, filed July 10, 1930, and which may be readily made in one piece and quickly operated in a particularly efficacious manner to securely fasten a piece of fabric such as a bandage or wrapping, by the simple expedient of hooking the fabric thereto then turning the element and fabric thereon throughout one complete revolution on the axes of the two spaced points of its affixation to a supporting means therefor.

A further object is to provide a clasp of the character described which combines a hook and button portion in a single piece of simple construction and which makes possible the advantages hereinbefore noted.

Yet another object is to provide a clasp of the character described having a small flexible yoke or support through which the clasp is turned in securing the same in place, the flexibility of the yoke or support permitting of close conformity of the entire clasp to curved surfaces and insuring comfort as well as otherwise improving the clasp as a whole.

With the foregoing objects in view together with such other objects and advantages as may subsequently appear, the invention resides in the parts and in the combination, construction and arrangement of parts as hereinafter described and claimed, and illus-

tated by way of example in the accompanying drawing in which:

Figure 1 represents a perspective view of a catamenial bandage support having the clasps of my invention incorporated therewith;

Figure 2 is a front elevation of one of the clasps as when in initial position;

Figure 3 is a sectional view taken on the plane of line 3—3 of Figure 2;

Figure 4 is a sectional view similar to Figure 3, showing the clasp as when partly moved from said initial position towards its operative position;

Figure 5 is a similar sectional view showing the clasp further advanced towards its final position;

Figure 6 is a similar sectional view showing the clasp in final or operative position;

Figure 7 is an enlarged front elevation of the clasp;

Figure 8 is a sectional view taken on the plane of line 8—8 of Figure 7;

Figure 9 is a top plan view of a modified form of the invention.

As shown in detail in the accompanying drawing, the present embodiment of the clasp of this invention comprises a button member 1 provided with a hook or prong 2 and spaced arms 3. The arms 3 are arranged to be secured in such manner, to a supporting means such as shown at 4, that the button portion and said arms, or in other words, the entire clasp, may be turned freely in either direction through three hundred and sixty degrees of arc. This movement of the clasp is necessary to secure the clasp to the bandage, or the like, to be held.

The first operation in using the clasp requires that an end or edge portion of the bandage or a like member, as here designated A, be hooked upon the front of the button portion 1 on the prong or hook 2, as shown in Figures 2 and 3. Next the clasp and fabric portion attached thereto are swung outward and upward, as shown in Figures 4 and 5, and turned through three hundred and sixty degrees of arc as aforementioned. This wraps the bandage or fabric member around the button portion so that said bandage or

member extends between the arms 3 and over the front of the button. Due to this wrapping, the portion of the fabric on the hook is relieved of strain and the likelihood of 5 tearing of the fabric is appreciably lessened. To release the clasp it is turned in the opposite direction back to the starting point and the bandage then may be easily removed. It is now apparent that the clasp may be 10 quickly and easily put into use and will lie close to the clothing or the body in flat and small compass so as not to form unsightly bulges or prove discomforting. But two movements, that of hooking the fabric on 15 the clasp, then the turning of the clasp, are necessary to reliably secure the bandage or fabric member to the clasp or vice versa. This, it will be noted, is an easier and quicker operation than possible with buckles, clasps 20 and like fastenings, such as heretofore used.

Preferably the button portion 1 is formed as an open square of suitable metal or other material. The prong or hook 2 is formed integral with the outer end of the button portion 25 centrally of the sides thereof and extends rearwardly across and beyond said portion with its pointed free end lying between the planes of the front and rear faces of the arms 3 whereby to prevent the said prong 30 from catching in the clothing or sticking the wearer or user of the clasp.

As here shown, the arms 3 are formed integral with the inner corner portions of the button 1 and extend divergently rearwardly 35 therefrom. Eyes 5 are formed in outer ends of said arms and provide for pivotal or swivel connection of the arms with the support means 4. The support means 4 may be any form providing a yoke through which the 40 clasp may be turned as aforesaid. As here shown, the yoke comprises two spaced flexible members 6 which may be made of elastic or inelastic material and serve as hangers. As shown in Figures 1 to 6 inclusive, two of 45 the clasps of this invention are used as a part of a catamenial belt 7 being attached as at 8 to the usual elastic tabs 9 and 10. These clasps are used in the manner aforementioned to clasp the ends of a catamenial bandage to 50 hold the latter in place.

It is obvious that the clasp may be used for many other purposes in connection with garments and otherwise, and in all cases the two flexible members 6 are employed as 55 shown in Figures 1 to 6 inclusive to secure the clasp in place. However, two clasps may be connected together by two of the flexible elements 6, as shown in Figure 9. The clasp arrangement shown in Figure 9 is ideally 60 adapted for holding bandages which are wrapped around the limbs or the body but may be put to many other uses for holding fabric wrappings or clothing in place. The elements 6 of the arrangement of Figure 9 65 are preferably but not necessarily elastic,

It should be noted that the clasp as shown herewith could be made to serve effectively for the purposes hereof without the hook or prong 2 although the latter positively prevents the clasp from coming undone and 70 facilitates the clasping operation from start to finish. However, if the hook is left off the clasp, the operator merely wraps the end of the bandage, or fabric to be secured, around the button portion so that said end extends 75 over the inner end of and behind the button. Following this, the operation of swinging the clasp completely around on the axes of the two points of affixation of the arms 3 thereof, is followed in same manner as hereinbefore 80 described. The wrapping of the fabric on the button resulting from this turning or reversing of the clasp causes a close and secure binding of the fabric on the clasp which binding tightens as the pull thereon increases. 85

I claim:

1. In a clasp, a button portion, spaced arms carried by and extending from one end of said portion, a hook on said portion, and supporting means pivotally connected with the 90 free ends of said arms and permitting of a complete revolution of the clasp on the axes of said pivotal connections.

2. In a clasp, a button portion, spaced arms carried by and extending from one end of 95 said portion, a hook on said portion, and supporting means pivotally connected with the free ends of said arms and permitting of a complete revolution of the clasp on the axes 100 of said pivotal connections, said means including spaced members to the outer ends of which said arms are connected and between which the clasp may swing.

3. In a clasp, a button portion, spaced arms carried by and extending from one end of 105 said portion, a hook on said portion, and supporting means pivotally connected with the free ends of said arms and permitting of a complete revolution of the clasp on the axes of said pivotal connections, said means including 110 spaced flexible members to certain ends of which said arms are connected as aforesaid.

4. In a clasp, a button portion, spaced arms carried by and extending from one end of 115 said portion, a hook on said portion, supporting means pivotally connected with the free ends of said arms and permitting of a complete revolution of the clasp on the axes of said pivotal connections, said means including 120 spaced flexible members to certain ends of which said arms are connected as aforesaid, and a prong on said button portion and on which said fabric member may be hooked.

5. In a clasp, a button portion, spaced arms 125 extending from one side of said portion, a support, flexible members fixed at respective ends to said arms and said support, and a prong fixed to said button portion and extending in front thereof to serve as a hook 130

on which is engaged the fabric piece which is to be held by the clasp.

6. In a clasp, a pair of spaced freely flexible members, a clasp element carried on said flexible members and connected thereto to swing a complete revolution around its connection therewith, and a prong carried by said element for engaging the material to be held by the clasp.
